UNITED STATES PATENT OFFICE.

WILLIAM H. EDSALL, OF BROOKLYN, NEW YORK.

CURTAIN-ROD.

SPECIFICATION forming part of Letters Patent No. 586,272, dated March 26, 1895.

Application filed December 26, 1894. Serial No. 532,918. (No model.)

To all whom it may concern:

Be it known that I, WILLIAM H. EDSALL, a resident of Brooklyn, Kings county, State of New York, have invented certain new and useful Improvements in Curtain-Rods, of which the following is a specification.

My invention relates to that class of curtain rods which are longitudinally expansible and designed to be held suspended self-sustaining between two opposing surfaces by the friction of the ends of the rod bearing upon the two surfaces.

To this end my invention consists in the construction hereinafter set forth, illustrated in the accompanying drawings, and more particularly pointed out in the claims.

My invention will be understood by reference to the accompanying drawings, forming part hereof, in which—

Figure 1 is a fragmentary elevation partly in longitudinal vertical section of one form of my invention, showing the same in position of use. Fig. 2 represents a side elevation of the top of the rod. Fig. 3 represents a spring which is inclosed in the top. Fig. 4 represents a fragment of the rod proper which enters the tube and bears against the spring. Fig. 5 represents a form of elastic button that may be used with my improved structure, the same being similar to the button shown in section in Fig. 1; and Fig. 6 is a side view partly in section of a modified form of button which may be used in my structure.

In the drawings, A is a suitable rod or tube having fitting over one end or both ends thereof a tubular section B. At some transverse plane in the length of the tubular section a suitable internal circumferential groove or enlargement b is formed, in which the bead or enlargement of the elastic button is seated, as will be hereinafter fully set forth. The end b' of the tube may be suitably formed or flanged, if desired, but I preferably form it, as shown.

D is a suitable button or plug preferably formed, as shown, that is to say, having a disk-like portion or flange d to bear against the end b' of the tubular section so as to prevent the button from being forced too far into the tube, a neck d' of less diameter than the diameter of the disk-like portion d, and a bead d² of larger diameter than the neck.

This button or plug D is recessed preferably on its inner end, with a recess d³ having the portion of its length included within the circumference of the bead d² formed with inclined walls, as at d⁴.

C is a spiral spring of such size as to readily enter the tube and preferably has one of its ends c, which is in contact with the button or plug, of a slightly larger diameter than the body of the spring.

My improved structure is set up as follows: The plug or button D which is made of india-rubber, wood or the like, but which is preferably elastic, is entered into the end b' of the tubular section B so that the bead d² registers with the circumferential groove or enlargement b. The spring is next entered into the tubular section at the end b² and pressed forward therein until its end c enters the recess d³ in the button or plug D and bears against the inclined wall d⁴ of such recess. It will now be obvious that when pressure is brought upon the spring C, the end c will enter or press against the plug D and force or expand the plug outwardly into the the circumferential bead or enlargement b or against the inner walls of the tube, whereby the button or plug D and the tubular section B will become firmly united. The tubular sections and plugs thus connected can be carried by one or both ends of the rod A, as shown in Fig. 1, and the interposed spring or springs serve to permit the structure to be compressed in the direction of its length, the rod and its tubular section or sections telescoping. The device may thus be applied to any desired use between two opposing surfaces.

In Fig. 1 I have shown the curtain rod as sustained self-supporting between two opposing surfaces E F, the curtain rod being longer than the distance between E and F, and being longitudinally compressed and sprung therein and held in place by the friction of its ends upon the surfaces E F, the expansive force of the spring or springs C serving to press the button or buttons against the opposing surfaces to thus hold the rod suspended self-sustaining between two opposing surfaces.

In the modification shown in Fig. 6 the button D' consists of the disk or flange-like portion, neck and bead d⁵, d⁶ and d⁷ respectively, and likewise with the recess d⁸, but instead of

the portion of the wall of the recess d^8 which is within the circumference of the bead d^7 , I provide a wall d^9 which is substantially parallel with the axis of the button D' and at a greater distance therefrom than the wall of the recess d^8 , so as to form an annular seat d^{10} for sustaining a portion of the impinging force of the spring. The arrangement and interaction of the parts when the button D' is used in lieu of the button D are the same as in the former case, that is to say, the disk or flange-like portion d^5 of the button comes against the end of the tube and prevents the button from moving longitudinally in one direction, to-wit, farther into the tube, while the spring bearing against the button and pressing it into the bead d^7 or against the inner wall of the tube prevents motion longitudinally in the opposite direction. The button may be made without any recess.

Now while I have specifically described a particular structure, I would have it understood that I do not thereby mean to limit myself to the structure thus set up, as it is obvious that the construction may be varied without departing from the spirit of my invention. For instance, it will be quite obvious that instead of enlarging or laterally expanding the tubular section by a circumferential groove or enlargement b , the tube may be otherwise constructed to help retain the rubber plug, and to have the plug take the impact of the spring. The instrument is theoretically complete without the tube which acts simply as a guide for the rod A , and to prevent the spring from collapsing. The plug D holds the tube in place for these purposes.

What I claim, and desire to secure by Letters Patent, is—

1. The combination of a tube, an elastic button entered into said tube and provided with a flange adapted to bear upon said tube to prevent longitudinal movement of the button in one direction, and a spring entered into the tube to contact with said button and serving to prevent longitudinal movement of the button in the other direction, substantially as described.

2. The combination of a tube, an elastic button entered therein, a spring entered into

the tube and serving to expand the button to hold the same from longitudinal movement, substantially as described.

3. The combination of a tube, a recessed elastic button entered into said tube, and a spring entered into the tube and into the recess in the button and serving to expand the button to hold the same from longitudinal movement in the tube, substantially as described. 62

4. The combination of a tube, a recessed elastic button entering said tube, a spring entered into the tube from the opposite end in which the button is entered and into the recess in the button and serving to expand the same to prevent the button from moving longitudinally in the tube, substantially as described. 65

5. The combination of a tube, an elastic button entered into the tube and provided with a recess with inclined walls as d^4 of a spring entered into the said tube and the recess in the button and bearing against the inclined wall thereof and serving to expand the button to prevent longitudinal movement of the button, substantially as described. 70

6. In a curtain rod, the combination of a tubular section having an enlargement of greater diameter than the body of the tubular section, a button or plug entering said enlargement, and a spring in the tubular section adapted to contact with said button, substantially as described. 80

7. The combination of a tube provided with an enlargement, a recessed elastic button provided with a bead, the said button being entered into the end of the tubular section in such a manner that its bead registers with the circumferential enlargement, and a spring entered into the end of the tube opposite to the end in which the button is entered and into the recess in the button and serving to expand the button to cause the bead thereof to bear against the wall of the enlargement to hold the button securely in the tube, substantially as described. 85 90 95
